UNITED STATES PATENT OFFICE.

WILLIAM HELMER, OF BOSTON, MASSACHUSETTS, ASSIGNOR TO AMERICAN SODA FOUNTAIN COMPANY, OF BOSTON, MASSACHUSETTS, A CORPORATION OF NEW JERSEY.

DESIGN FOR A GLASS-HOLDER OR SIMILAR ARTICLE.

No. 38,208.

Specification for Design.

Patented Aug. 28, 1906.

Application filed July 30, 1906. Serial No. 328,484. Term of patent 7 years.

To all whom it may concern.

Be it known that I, WILLIAM HELMER, a citizen of the United States, and a resident of Boston, in the county of Suffolk and State of Massachusetts, have invented a new, original, and ornamental Design for Glass-Holders or Similar Articles, of which the following is a specification, reference being had to the accompanying drawing, forming a part hereof, which is a perspective view of said design.

What I claim is—

The ornamental design for a glass-holder or similar article as shown.

WILLIAM HELMER.
